(57) **CLAIM**

The ornamental design for a weightlifting grip, as shown and described.

DESCRIPTION

FIG. 1 is a top isometric view of the weightlifting grip;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The short dashed lines of uniform length represent an ornamental appearance of the claimed design. The short-short-long dashed lines represent environment, and do not constitute a portion of the claimed design. Any shading and cross-hatching are not features of the design but are utilized to illustrate the surface contours of the weightlifting-grip design in the drawings.
